CASPER MEHLUM, OF CAMBRIDGE, MASSACHUSETTS.

MACHINE FOR MAKING FIBER TUBES.

1,069,971.

Specification of Letters Patent. Patented Aug. 12, 1913.

Application filed December 26, 1912. Serial No. 728,573.

To all whom it may concern:

Be it known that I, CASPER MEHLUM, a subject of the King of Norway, residing at Cambridge, county of Middlesex, State of Massachusetts, have invented a certain new and useful Improvement in Machines for Making Fiber Tubes, of which the following is a specification, reference being had therein to the accompanying drawings.

- 10 In the manufacture of fiber tubes as sometimes practised, the material from which the tube is formed is prepared in a sheet or web wound into a roll from which it is rewound on a mandrel for a sufficient number 15 of layers or windings to make a tube of the requisite thickness, the web passing through an acid bath on the way from the web roll to the mandrel. When the tube has been built up to the requisite thickness the web is 20 cut so as to free the unwound portion of the web from the portion on the mandrel, and the tube thus formed is removed from the mandrel. The mandrel is mounted on a shaft journaled in suitable bearings, and for 25 the purpose of conveniently withdrawing the tube from the mandrel endwise it is desirable to have one of the bearings removable with relation to the shaft so as not to interfere with the withdrawing of the tube. 30 One feature of my invention relates to an improved movable bearing, and means for moving it.

Other features of the invention relate to the means for starting and stopping the machine.

There are still other features of the invention all of which will be hereinafter fully described.

The invention will be fully understood 40 from the following description taken in connection with the accompanying drawings, and the novel features will be pointed out and clearly defined in the claims at the close of the specification.

45 In the drawings: Figure 1 is an end elevation partly broken away of a machine embodying the invention, as viewed from the right of Fig. 2. Fig. 2 is a front elevation partly in section, the middle portion of the 50 mandrel and the connected parts being broken away for convenience of room. Fig.

3 is an end elevation viewed from the opposite end from Fig. 1, that is, viewed from the left hand end of Fig. 2. Fig. 4 is a sectional detail on a reduced scale of the mandrel and its operative parts viewed when the mandrel is collapsed. Fig. 5 is an end view of the collapsed mandrel, partly in section. Fig. 6 is a detail view showing the means for automatically stopping the machine. Fig. 7 is a section on line 7—7 of Fig. 1.

Referring now to the drawings,—1 represents the frame or bed of the machine.

2 represents the web or sheet which is run from a roll, not shown, through the acid 65 bath 3 in the tank 4, thence between the scrapers 5—5 to remove the surplus acid and passes up over and under the presser roll 6, thence around the mandrel A. As the tube hugs the mandrel very tightly the 70 mandrel should preferably be of a collapsible type so that the built up tube can be removed. The preferred form is that shown in the drawings and which is made the subject of a divisional application hereof Serial No. 751,792, but it is shown and described herein for the purpose of explaining the invention of this application, although it is to be understood that the claims herein are not to be limited to use 75 with the particular form of mandrel herein shown.

In the preferred form of construction the mandrel A is composed of a plurality, preferably four in number, of segmental plates 85 7, each of which is a quarter cylinder of the same radius, so that when matched together the four plates together will form a cylinder. Preferably the edges 8 of each one of the segmental plates is beveled; as shown in Fig. 5, so that the plates may more readily slide over each other to collapse the mandrel. Each segmental plate has secured to its inner face a series of ears 9, to which is pivotally connected a series of hangers 95 10 which form supports for a bar or rod 11. A shaft 12 passes lengthwise through the center of the mandrel, and has fixedly mounted thereon a series of boxes 13 which are pivotally connected with the several longitudinal bars 11 by means of the links 14 100 which are pivoted both to the bars 11 and

the boxes 13. The front end of each of the bars 11 is pivotally connected by links 15 with a hub or collar 16 mounted fast on a sleeve 17 in which the shaft 12 is slidable. Means are provided to cause the shaft 12 and sleeve 17 to rotate together as will be hereinafter described. Preferably the front ends of the bars 11 are formed with a bent portion 18 for convenience of connecting with the links 15. The sleeve 17 through which the shaft 12 passes is mounted in bearings 19 in the frame 20 while the other end of the shaft rests in a semi-cylindrical bearing 21 mounted on a swinging bracket 22 for the purpose of enabling the bearing to be swung out of engagement with the shaft, as will be hereinafter described. This bracket 22 is formed with ears 23 which are perforated to allow the hinge pin 24 to pass loosely through said ears whereby the said bracket is hinged on said pin 24. The said pin 24 is mounted fast in lugs 25 which project from the upright portion 261 of the frame of the machine. The lower ear 23 rests upon the hub 26 of an arm 27, said hub 26 being perforated to allow the loose passage of the pin 24 through said hub, the arm 27 resting upon a cam 28 mounted on a shaft 29. Said cam 28 is adapted, when the high part of said cam is in engagement with said arm 27, to hold said arm and therefore the bearing bracket 22 in the position shown in Fig. 3, but when said cam is rotated, bringing the lower part of the cam into engagement with the arm 27, said arm 27 will descend under the pressure of the bearing bracket 22, allowing the bearing bracket to drop down with it, thereby freeing the semi-cylindrical bearing 21 from the shaft 12, and the bearing bracket 22 can also be swung around on the pin 24 entirely free from its transverse position across the end of the mandrel. The shaft 29 on which cam 28 is mounted is actuated by means of a crank arm 67 mounted fast on the shaft and provided with a handle 68.

Mounted fast on the forward end of the sleeve 17 is a gear wheel 30 which engages with a gear 31 mounted on a shaft 32. Projecting from the face of the gear 30 is an arm 33 to which is pivotally connected a handle 34 which has a link connection 35 with the forward end of the shaft 12, so that by means of said handle 34 the shaft 12 can be moved longitudinally in its bearings. By reason of the connection of the handle 34 with both the gear 30 and the shaft 12, said shaft 12 will rotate with said gear and with the sleeve 17. Means are provided for locking the handle to the gear 30 when the mandrel is in expanded form so that it will not be accidentally moved to collapse the mandrel.

Pivoted to the side of the handle 34 is a

lever 105 carrying a stud 106 which extends through a hole in the handle and is adapted to engage in a hole in an arm 36 which projects from the side of the gear 30. A spring 107 normally holds the stud 106 in engagement with said hole in the arm 36, as shown in Fig. 1, to lock the handle so that the shaft 12 will not be moved longitudinally, but will be free to rotate with the gear 30 and sleeve 17. By pressing on one arm of said lever, the lever will be turned to disengage the pin from the socket in the arm 36 so that the handle may be pulled back, as shown in Fig. 4, thereby pulling the links 14 into the angular position shown in said Fig. 4 and drawing the bars 11 inward toward the shaft and thereby drawing the segmental plates 7 inward into the position shown in Fig. 5 nearer to the shaft. The pivoted side of each segmental plate 7 will slide partially under the free side of the adjacent segment.

Mounted fast on shaft 32 is a pulley 37 driven by a belt 38, thereby driving gears 31 and 30 to rotate the mandrel. Mounted loose on said shaft 32 is a pulley 39. Slipping bars 40 extend on either side of the belt 38, being mounted on an endwise movable shaft 41, whereby the belt may be shifted from the fast pulley to the loose pulley or the reverse, so that when the belt is shifted to the loose pulley the shaft 12 and the mandrel will be stopped from rotation. A hand lever 42 having a link connection 43 with the shaft 41 is provided whereby the shaft may be moved endwise to shift the belt.

Mounted fast on the sleeve 17 of shaft 12 is a worm 44 which engages with a worm gear 45 on the shaft 46. Mounted loose on the shaft 46 is a pinion 49 with which a clutch 50 which is fast on said shaft is adapted to engage to cause the said pinion to rotate with the shaft. A spring 51 coiled around said shaft 46 normally holds the clutch in engagement with the pinion 49 so that the pinion will revolve with the shaft. A vertical rack bar 52 engages with said pinion 49 and is slidable in guides 53. A stop 54 limits the downward movement of the rack bar. Projecting from the rack bar 52 is a stud 55 which is preferably adjustable vertically on said rack and which as the rack rises is adapted to engage one arm 56 of a three arm lever 57 pivoted on stud 58 to slightly turn said lever 57. A lever 61 pivoted on said stud 58 projecting from the frame of the machine engages an annular groove in clutch 50. A second arm 59 of said three arm lever is adapted to engage a pin 60 on said lever 61 to disengage said clutch 50. A third arm 62 of said three arm lever extends downward and is normally in engagement with a cam faced block 63 on the shaft 41 to prevent the endwise movement of the shaft 41.

in a direction to throw the belt from the fast to the loose pulley. A spring 64 which is coiled around the shaft 41 normally under compression between one of the bearings 65 of the shaft 41 and the head 66 of said shaft causes the said shaft to move endwise to the left as viewed in Fig. 2 when the arm 62 is released from engagement with the said stop block 63. In the upward movement of the 10 rack 52 when the stud 55 turns the three arm lever 57, as already described, the said arm 62 will be moved far enough to just clear the tapered end of the cam block 63, and not far enough to disengage the clutch 50. Now the 15 shaft 41 is free to respond to the pull of the spring 64 and the cam face of the block 63 will engage the side of the arm 62 and thereby turn the three arm lever 57 still farther on its pivot so that arm 59 will move far 20 enough to engage pin 60 on lever 61 and move lever 61 far enough to disengage the clutch. The endwise movement of shaft 41, above described, will shift the belt from the fast pulley to the loose pulley. This movement of the three arm lever will stop the 25 entire machine. As soon as the clutch 50 is disengaged from the gear 49 said gear being loose on the shaft 46 the weight of the rack bar will cause it to descend by gravity, the 30 said gear revolving on its shaft, and said rack will descend until its lower end engages with the stop 54.

The presser roll 6 is journaled in bearings on a lever 69 pivoted at 70 to a bracket 71 mounted on the frame of the machine. The other end of said lever 69 opposite the end which carries the presser roll 6 is pivotally connected with one end of a connecting rod 72, the other end of said connecting rod being 35 pivotally connected with an arm 73 mounted fast on the shaft 29. When said shaft 29 is rocked to carry the high part of the cam 28 out from under the arm 27 which supports the swinging bearing bracket 22 it 40 will turn the arm 73 down and thereby bring down the connecting rod 72 and turn the lever 69 on its fulcrum so as to lift the presser roll 6 out of engagement with the built up tube on the mandrel, and when said 45 arm 67 is turned to bring the high part of the cam 28 again into engagement with the arm 27 it will bring the arm 73 up into the vertical position again, as shown in Fig. 3, thereby lifting the connecting rod 72 and 50 turning the lever 69 in a direction to bring the presser roll 6 again down into engagement with the mandrel or with the tube on the mandrel.

In order to adapt the presser roll 6 for 55 different sizes of mandrels the pivot 70 for the lever 69 is mounted in an adjustable block 74 which is adjustable in the bracket 71, the adjustment being secured by means of a screw 75 which also holds the pivot

block 74 in its adjusted position. The connecting rod 72 also is provided with a plurality of slots 76 for the purpose of adjusting the point of connection of the lever 69 with said connecting rod 72 according to the variation in the adjustment of the pivot 70.

At the beginning of the operation of the machine the lower end of the rack bar 52 will rest on the step 54. As the rotation of the mandrel will continue until the stud 55 strikes the arm 56 of the three arm lever to 55 stop the machine, it is obvious that the number of rotations of the mandrel, and therefore the number of thicknesses of plies of the sheet of fiber will depend upon the length of the stroke of the rack bar 52. By 60 varying the length of stroke of the rack bar 52 the number of plies of the web may be varied. For this reason the stud 55 is made adjustable up and down on the rack bar. In order to determine the point to which the 65 stud 55 should be adjusted for any particular number of windings of the web the rack bar is provided with a scale 77. Preferably the scrapers 5—5 are also adjustable. These scrapers are mounted on a block 78 which is 70 itself mounted on a shaft 79, said shaft 79 being supported in bearing arms 80. Said arms 80 are supported on a stud 81 secured to a standard 82. The arm 80 has an elongated slot 83 and said stud 81 is adjustable 75 therein to vary the length of the operation of the arm 80 which carries the block 78 and said standard 82 is also provided with a vertical elongated slot 84 whereby a vertical adjustment is given to the arm 80 so that 80 by adjusting the arm 80 both horizontally and vertically the arm 78 may be adjusted up and down as well as toward and from the standard 82. In addition to these adjustments the scrapers 5 may be adjusted to vary 85 their angle with relation to the arm 78 by loosening the clamp screws 85 which secure them to the arm 78 and then tightening up the said screws.

The operation of the machine is as follows:—Starting with the parts in the position shown in Figs. 1 to 3, the mandrel being all set up and supported in its bearings at each end, the driving belt being engaged with the tight pulley 37, and the rack 52 being in its lowermost position, and the web 2 threaded up over the presser roll 6 and down underneath the presser roll onto the mandrel. As the driving wheel rotates, the gear 31 will cause the gear 30 to rotate and thereby rotate the shaft 12 and the mandrel until the rack 52 has been raised by the pinion 49 far enough for the stud 55 to engage the arm 56 of the three arm lever 57 and turn the said lever slightly on its fulcrum. The arm 62 will thus be turned back out of engagement with the tapered end of the block 63 on the shaft 41 and engages the cam face of the

block so that shaft 41 may respond to the pull of the spring 64 and thereby cause the shipper arms 40 to move the belt 38 from the fast pulley to the loose pulley 39 and therefore stop the mandrel. The continued pull of the spring 64 on the shaft 41 will cause the cam faced block 63 to turn the three arm lever still farther on its fulcrum, as already described, to cause the arm 59 to actuate the lever 61 to disengage the clutch 50 and stop the rotation of shaft 46. As soon as clutch 50 is disengaged from the gear 49 the rack 52 will drop until it strikes the stop 54, as already described. The operator will then by hand release the lever 34 from its locked engagement with the gear wheel and turn it over to the right from the position shown in Fig. 2 to that shown in Fig. 4 pulling the shaft 12 longitudinally to the right and thereby pulling the links 14 from their vertical position shown in Fig. 2 to the angular position shown in Fig. 4, and pulling the links 15 more nearly parallel with the shaft, and thereby drawing the pivoted sides of the segments 7 inwardly, as shown in Fig. 5, which will be allowed by reason of the beveled edges of said segment plates, thus partially collapsing the mandrel so that the built up tube will be loose on the mandrel. The operator will then pull the lever 67 to the right from the position shown in Fig. 3, so as to bring the high part of the cam 28 out from engagement with the under side of the arm 27, so that the arm 27 will drop, thereby allowing the bracket 22 to drop out of engagement with the shaft 12. Then said bracket 22 will be swung around on its pivot so that there will be no obstruction to pulling the fiber tube endwise off of the collapsed mandrel. Before attempting to withdraw the tube from the mandrel the web of fiber will be cut with a knife to sever the unwound portion from the tube portion. When it is desired to start the machine again the swinging bearing 22 will be swung around into its position transversely of the end of the mandrel and the lever 67 will be turned so that the cam 28 will lift the arm 27 and thereby lift the bracket bearing into position to engage the shaft 12. The lever 34 will be turned up into vertical position and locked so as to expand the mandrel and retain the shaft against endwise movement. Then the lever 42 will be turned to the right into the position shown in Fig. 2 so as to shift the driving belt 38 from the loose pulley back onto the tight pulley, and then the machine will start for another cycle of movement.

The presser roll 6 is preferably heated so that it will warm the acid in the sheet and make it stick to the sheet underneath.

The arm 56 of the three arm lever is preferably provided with a counter weight 86 to cause the said lever to swing back on

its pivot into the normal position of Fig. 1 65 when it is free to do so.

I claim—

1. In a machine for making fiber tubes, a mandrel on which the tube is built up, means for rotating said mandrel, means for disengaging the driving mechanism for said mandrel, a vertically reciprocable member, clutch and gear connection whereby the rotation of said mandrel driving mechanism raises vertically reciprocable member, 70 means whereby said vertically reciprocable member when it reaches a predetermined elevation controls the operation of the disengaging means of the driving mechanism to stop the rotation of the mandrel, and means controlled by the movement of said disengaging means for the driving mechanism of the mandrel to also disengage the clutch of the driving connection which raises said vertically reciprocable member, 75 said vertically reciprocable member being free to automatically drop to its initial position when said driving connection is disengaged.

2. In a machine for making fiber tubes, a mandrel on which the tube is built up, means for rotating said mandrel, a vertically reciprocable member, intermediate mechanism whereby said reciprocable member is raised by the rotation of the mandrel, a rocking lever, one arm of which is engaged by said reciprocable member at a predetermined point in its upward movement to turn said lever through a portion of its stroke in one direction and separate means controlled by 90 said partial stroke of the lever to still further rock the lever and thereby stop the rotation of the mandrel.

3. In a machine for making fiber tubes, a mandrel on which the tube is built up, means for rotating said mandrel, a vertically reciprocable member, intermediate mechanism whereby said reciprocable member is raised by the rotation of the mandrel, a rocking lever, one arm of which is engaged by said reciprocable member at a predetermined point in its upward movement to turn said lever through a portion of its stroke in one direction and separate means controlled by 105 said partial stroke of the lever to still further rock the lever and thereby stop the rotation of the mandrel, said additional movement of said lever disengaging the driving connection which elevates the said reciprocable member, said reciprocable member being thereby rendered free to automatically descend to its initial position.

4. In a machine for making fiber tubes, a mandrel on which the tube is built up, means for rotating said mandrel, a vertically reciprocable member, intermediate mechanism whereby said reciprocable member is raised by the rotation of the mandrel, a three arm

rocking lever, one arm of which is engaged by said reciprocable member at a predetermined point in its upward movement to turn said lever through a portion of its stroke in one direction, means for disengaging said driving mechanism from driving connection with the mandrel, means whereby a second arm of said rocking lever normally holds in check said disengaging mechanism, said second arm being moved out of restraint on said disengaging mechanism by said partial movement of the lever whereby said disengaging mechanism is rendered operative, the movement of said disengaging mechanism still further rocking said lever, and means whereby said further movement of the rocking lever causes the third arm of said lever to disengage the driving mechanism which elevates said vertically reciprocable member, said vertically reciprocable member being free to drop to its initial position when the driving mechanism is disengaged.

5. In a machine for making fiber tubes, a mandrel on which the tube is built up, means for rotating said mandrel, means for disengaging the driving mechanism for said mandrel, a vertically reciprocable member, clutch and gear connection whereby the rotation of said mandrel driving mechanism raises said vertically reciprocable member, means whereby said vertically reciprocable member when it reaches a predetermined elevation controls the operation of the disengaging means of the driving mechanism to stop the rotation of the mandrel, and means controlled by the movement of said disengaging means for the driving mechanism of the mandrel to also disengage the clutch of the driving connection which raises said vertically reciprocable member.

6. In a machine for making fiber tubes, a mandrel on which a web is wound to build up the tube, a rotary shaft on which the mandrel is mounted, driving mechanism for actuating said mandrel shaft, a vertically reciprocable member, a rotary shaft having intermediate connections whereby said reciprocable member is raised and having connection with the mandrel shaft whereby said shaft which actuates said reciprocable member is actuated by the said mandrel shaft, a three arm lever having one arm which is adapted to disengage the driving connection with said reciprocable member and having another arm which is adapted to control the disengaging of the driving mechanism from driving connection with the mandrel shaft and having a third arm which is engaged by a projection on said reciprocable member at a predetermined point in the upward movement of said reciprocable member whereby the driving mechanism is disengaged from the mandrel shaft.

7. In a machine for making fiber tubes, a

mandrel on which a web is wound to form the tube, a rotary shaft on which said mandrel is mounted, a vertically reciprocable rack bar, a rotary shaft on which is loosely mounted a pinion engaging with said rack bar and adapted to lift the said bar, clutch connection between said pinion and said shaft whereby when the clutch is engaged the rack bar will be lifted, a driving mechanism having driving connection with said mandrel shaft, driving mechanism which is adapted to disconnect the driving mechanism from driving connection with said mandrel shaft, means including a pivoted lever for normally retaining said driving mechanism in operative connection with the mandrel shaft, a projection on said rack bar which when the rack has been raised a predetermined distance turns said lever and causes the mandrel shaft to stop rotation, and means actuated by the movement of the shipper for the driving mechanism of the mandrel shaft to trip the clutch of the rack bar shaft.

8. In a machine for making fiber tubes, a rotary mandrel on which sheets of fiber are wound to form a tube, a rotary shaft on which said mandrel is mounted, driving mechanism therefor, a vertically reciprocable rack bar, gear connection between said rack bar and said mandrel whereby the rotation of the mandrel shaft raises the rack bar, said gear connection including a shaft on which the rack engaging gear is loosely mounted, clutch connection between said rack engaging gear and said gear actuating shaft, a clutch lever connected with said clutch, a three arm lever having one arm which is adapted to engage said clutch lever to disengage the clutch, a projection carried by said rack bar which is adapted to engage another arm of said three arm lever on the upward movement of the rack at a predetermined point to partially turn said lever, a slidable shaft carrying a shipper which is adapted to disengage the driving mechanism from operative connection with the mandrel shaft, a cam block on said shipper shaft which is normally engaged by the third arm of said three arm lever to prevent movement of the shipper shaft, said three arm lever being turned by the engagement of the stop on the rack bar with said second arm of said lever to move said third arm out of stop engagement with said cam block, means whereby said shipper shaft will then be moved to disengage the driving mechanism of the mandrel actuating shaft, and thereby stop the rotation of the mandrel, the said movement of the shipper shaft causing said cam block to still further turn the said three arm lever and thereby disengage the clutch of the rack bar pinion.

9. In a machine for making fiber tubes, a

mandrel on which the tube is built up, means for rotating said mandrel, means for disengaging the driving mechanism for said mandrel, a reciprocable member, clutch and gear connection whereby the rotation of said mandrel driving mechanism moves said reciprocable member in one direction, means whereby said reciprocable member when it reaches a predetermined position controls the operation of the disengaging means of the driving mechanism to stop the rotation of the mandrel, and means controlled by the movement of said disengaging means for the driving mechanism of the mandrel to also disengage the clutch of the driving connection which moves said reciprocable member.

10. In a machine for making fiber tubes, a rotary mandrel, a rotary shaft on which said mandrel is mounted, driving mechanism for said mandrel, a vertically reciprocable stop, intermediate mechanism including therein clutch mechanism whereby the driving mechanism of the mandrel raises said stop, a shipper which is adapted to disengage the driving mechanism from operative connection with the mandrel shaft, mechanism which normally prevents movement of the shipper, and which is moved to release said restraint by the upward movement of said stop, mechanism which when said restraint is released actuates the said shipper to disengage the driving mechanism of the mandrel shaft, said restraining mechanism for the shipper being further actuated by the movement of the said shipper to disengage from driving connection with the stop the elevating mechanism thereof, said stop being automatically returned to its normal position when said elevating mechanism is disengaged.

11. In a machine for making fiber tubes, a mandrel on which the tube is built up, means for rotating said mandrel, a reciprocable stop, intermediate mechanism whereby said stop is moved by the rotation of the mandrel, a three arm lever, one arm of said lever being engaged by said reciprocable stop at a predetermined point in its movement to turn said lever, means controlled by the movement of a second arm of said lever when said lever is turned by said stop to stop the rotation of the mandrel and also to still further turn said lever, and means actuated by a third arm of said lever during said further turning to disengage the stop raising mechanism and allow the stop to return to its normal position.

12. In a machine for making fiber tubes, a mandrel, a rotary shaft on which said mandrel is mounted, a driving shaft, driving connections between said mandrel shaft and said driving shaft, a longitudinally mov-

able shifter shaft and means actuated thereby to disengage driving connection with the mandrel shaft, a spring which tends to pull the shifter shaft in a direction to disengage said driving connection, a cam mounted on said shifter shaft, a lever mounted on a rocker shaft having one arm which normally engages said cam and prevents the longitudinal movement of said shifter shaft, a vertically movable bar carrying a stop projection, said lever having an arm which is engaged by said stop when said bar has reached a certain elevation, intermediate mechanism connected with said mandrel shaft whereby said vertically movable stop is raised, thereby turning said lever when the mandrel has rotated a predetermined number of times giving to said lever an initial rocking movement to partially release the first arm of said lever from said stop cam whereby the pull of said spring on the shifter shaft causes the engagement of a cam face on said cam with said lever to further turn said lever, thereby allowing the disengaging of said driving connection with the mandrel shaft, clutch mechanism connected with said vertically movable stop carrying bar and its elevating mechanism, said rocking lever also having an arm which throws said clutch when said rocking lever is moved by said cam, thereby disengaging said vertically movable bar from its driving connection and allowing it to return to its normal lowermost position.

13. In a machine for making tubes, a mandrel, a shaft which extends centrally through said mandrel, a hinged arm which has a bearing for said shaft at one end of the mandrel, a pintle for said arm on which the arm swings horizontally and is movable vertically, a movable bottom support for said hinged arm, movable means for holding said bottom support in position, whereby the arm is normally held in its uppermost position to retain the bearing in engagement with the shaft, and means for moving said holding means for the support to allow the dropping of said arm and bearing.

14. In a machine for making tubes, a mandrel, a shaft which extends centrally through said mandrel, a hinged arm which has a bearing for said shaft at one end of the mandrel, a pintle for said arm on which the arm swings horizontally and is movable vertically, a vertically movable support for said hinged arm, a rotary cam which engages said support and is adapted to hold said support in its upper most position and to be turned to allow said support to drop and also to be turned to raise said support.

15. In a machine for making fiber tubes, a rotary mandrel, a shaft which extends centrally through said mandrel, a hinged

bracket bearing for said shaft at one end of the mandrel, said bracket being movable vertically on its pintle, and hinged to swing horizontally away from the end of the mandrel, a movable support for holding said bracket normally in its elevated position and which is movable to allow said bracket to drop, a rotary cam for controlling the raising and lowering of said support, a presser roll, a pivoted lever carrying said presser roll which is adapted to bear against the tube while being formed on the mandrel, connections between said lever and said cam whereby when the said bracket is lowered the presser roll will be released from engagement with the tube on the mandrel and whereby when the bearing is raised again the presser roll will again be engaged with the tube.

In testimony whereof I affix my signature, in presence of two witnesses.

CASPER MEHLUM.
